UNITED STATES PATENT OFFICE

2,289,154

ARTIFICIAL LIMB

Clifford W. Van Cise, Sharon, Pa.

Application December 24, 1941, Serial No. 424,363

2 Claims. (Cl. 3-6)

This invention relates to an improved artificial limb including a foot and leg, and more particularly to an improved ankle joint for the artificial limb located to provide for the greatest flexibility between the foot and leg portions thereof by locating the joint in the position of the natural ankle joint to thereby produce a life-like action between the parts of the limb.

Another object of the invention is to provide an artificial limb wherein the pivotal movement of the ankle joint is resisted by yieldable means which are adjustable for providing the desired amount of action in the joint to suit the wearer.

Another aim of the invention is to provide cushioning means for cushioning the shock to the leg of the wearer when walking with the artificial limb and which eliminate pressure points on the stump.

Still a further aim of the invention is to provide a ball and socket connection forming the ankle joint to permit the universal movement of the foot relatively to the leg.

Other objects and advantages of the invention will hereinafter become more fully apparent from the following description of the drawing, which illustrates a preferred embodiment of the invention, and wherein:

Figure 1 is a fragmentary vertical sectional view, partly in side elevation of the artificial limb.

Figure 2 is a fragmentary transverse vertical sectional view of the same, taken substantially along a plane as indicated by the line 2-2 of Figure 1.

Figures 3 and 4 are horizontal sectional views taken through portions of the artificial limb and substantially along the planes as indicated by the lines 3-3 and 4-4, respectively, of Figure 1, and

Figure 5 is a modification of the parts shown in Figure 3.

Referring more particularly to the drawing, wherein like reference characters designate like or corresponding parts throughout the different views, 10 designates generally the artificial limb in its entirety and including a leg 11 and a foot 12.

The leg 11 includes an upper, hollow shin portion 13 which is adapted to receive the stump and a lower, substantially solid portion 14 having an upwardly opening, substantially centrally disposed socket 15 which opens into a hollow interior 16 of the shin portion 13, and a similarly disposed downwardly opening socket 17, which opens outwardly of the lower end of the leg 11. 55

The inner ends of the sockets 15 and 17 are connected by an opening 18.

The foot 12 includes an upper portion 19, which portion and the leg 11 are formed of a suitable rigid material. The foot 12 also includes an integral toe and sole portion 20, formed of a resilient material such as rubber. A plate 21 of resilient metal is anchored in the toe part of the resilient portion 20 and has one end projecting therefrom and secured to the under side of the foot portion 19 by fastenings 22. The plate 21 forms resilient reinforcing means for the toe of the foot 12.

The upper foot portion 19 is provided with an upwardly opening recess or socket 23 containing a socket member 24 which is anchored therein by means of pins 25. The socket member 24 is provided with an annular inwardly bowed upper portion 26 which extends above the upper surface 27 of the foot portion 19 and which is provided with a restricted opening 28. A pin 29 extends across the socket 24, adjacent its upper end, and is disposed transversely of the foot 12. A graphite bushing 30 is turnably mounted on the pin 29.

The upper surface 27 is curved upwardly toward its forward end and is likewise curved upwardly slightly toward its rear end. The lower end of the leg 11 forms a surface 31 which is likewise curved upwardly at its forward and rear ends and which is disposed substantially parallel to the surface 27. Between the surfaces 27 and 31 is mounted a block 32 of resilient material such as rubber, and which is of substantially the same shape as the surfaces 27 and 31. The block 32 is provided with a central opening 33 into which the socket end 26 extends and into which opens the socket 17. A bolt 34 is provided with a substantially ball-shaped head 34 which is provided with a slot 35. The slot 35 opens downwardly and laterally and the pin 29 and the bushing 30 extend therethrough and the ball-shaped head 34 is disposed in the upper part of the socket 24. The bolt 34 is provided with a threaded shank 36 which extends upwardly from the head 34 through the openings 28 and 32, through the socket 17, opening 18 and socket 15 and into the socket 16.

As best seen in Figure 3, the socket 17 is polygonal shaped cross section and is provided with a similarly shaped lining 37 in which is slidably mounted a block 38, which is likewise shaped to conform to the lining 37 to prevent the block from turning therein. The block 38 is provided with a central opening through which the shank

36 extends and is adjustably secured thereto by means of nuts 39 which engage guide block 38, thereabove and therebeneath.

An elongated block 40 of yieldable material, is mounted in the socket 15 and extends into the socket 16 and is provided with a washer 41 at each end thereof. The block 40 and washers 41 are provided with aligned openings through which the shank 36 extends. A bolt nut 42 engages the shank 36 and bears against the upper washer 41 and a lock nut 43 engages the shank 36 and bears against the upper side of the nut 42.

From the foregoing, it will be obvious that the yieldable block 32 is disposed substantially at the level of the human ankle joint so that the joint formed by the socket 24 and the bolt 33 will be disposed in substantially the same location as the human ankle joint. The ball and socket connections formed by these parts permit the bolt 33 to rock forwardly or rearwardly or laterally to the foot 12 and this rocking motion will be resisted by the yieldable block 32 to provide a yielding pivotal movement which can be varied by adjusting the nuts 42 and 43. The guide 38 will prevent any turning movement of the bolt 33 relatively to the socket 34 and will therefore prevent the foot 12 from turning relatively to the leg. The bushing 30 is spaced from the inner end of the slot 35 to allow the bolt to move downwardly when weight is applied to the limb member from above so that the block 32 can cushion the shock which occurs when the weight of the wearer is applied to the artificial limb 10, as in walking. Likewise, the block 40 is compressed to permit the leg and foot to yield away from one another. The yieldable toe and sole portion 20 will further act to cushion the shock which occurs in walking. It will thus be apparent that the artificial limb 10, while of very simple construction, can be worn very comfortably and will have a very life-like action.

If desired, and as illustrated in Figure 5, the bottom socket of the leg can be made circular in cross section, as indicated 17a, and can be provided with a lining 37a which can be pressed therein to prevent the lining from turning relatively to the socket, and which can be provided with a polygonal shaped bore to receive and slidably mount the guide 38. Various other modifications and changes are contemplated and may obviously be resorted to, provided they fall within the spirit and scope of the invention as herein-after defined by the appended claims.

I claim as my invention:

1. An artificial limb comprising a substantially rigid leg, a foot having an upper part of substantially rigid material, a yieldable member disposed between the leg and said upper part of the foot, means for pivotally connecting the upper part of the foot to the leg, said connecting means combining with the yieldable member to provide a limited resilient, pivotal movement between the foot and leg, said connecting means including an upwardly opening socket member anchored in the upper foot portion and having a restricted upper end, said yieldable member having an opening into which the upper end of the socket member extends, a bolt having a ball-shaped head disposed in the upper end of the socket member and provided with a slot which opens outwardly, downwardly and laterally of the limb, a pin extending through the socket member and through the slot in the bolt head, and said bolt having an upwardly extending shank which extends into and is adjustably secured to the leg.
2. An artificial limb comprising a substantially rigid leg, a foot having an upper part of substantially rigid material, a yieldable member disposed between the leg and said upper part of the foot, means for pivotally connecting the upper part of the foot to the leg, said connecting means combining with the yieldable member to provide a limited resilient, pivotal movement between the foot and leg, said connecting means including an upwardly opening socket member anchored in the upper foot portion and having a restricted upper end, said yieldable member having an opening into which the upper end of the socket member extends, a bolt having a ball-shaped head disposed in the upper end of the socket member and provided with a slot which opens outwardly, downwardly and laterally of the limb, a pin extending through the slot in the bolt head, said bolt having an upwardly extending shank which extends into and is adjustably secured to the leg,

CLIFFORD W. VAN CISE.
